(57) **CLAIM**

The ornamental design for a portion of a top rail, side and edge of a headboard, as shown and described.

DESCRIPTION

FIG. 1 is a portion of a top rail, side and edge of a headboard, showing my new design.

FIG. 2 is a left-side elevational view thereof;

FIG. 3 is a rear elevational view thereof;

FIG. 4 is a right-side elevational view thereof;

FIG. 5 is a top plan view thereof; and,

FIG. 6 is a bottom plan view thereof.

The broken lines shown in the figures for portion of a top rail, side and edge of a headboard are for purposes of illustration and form no part of the claimed design.
